DISPENSING APPARATUS FOR OILS AND THE LIKE.

1,302,014.

Specification of Letters Patent. Patented Apr. 29, 1919.

Application filed March 6, 1917. Serial No. 152,642.

To all whom it may concern:

Be it known that I, JOHN B. DAVIS, a citizen of the United States of America, residing at Springfield, in the county of Hampden and State of Massachusetts, have invented certain new and useful Improvements in Dispensing Apparatus for Oils and the like, of which the following is a specification.

10 This invention relates to dispensing apparatus or pumps. The complete apparatus is designed particularly for outdoor use and consists of an improved "filling station" for automobiles, as an example. The invention, however, embodies new and improved structure in dispensing pumps generally. The invention, therefore, consists in the complete apparatus broadly comprising an improved "filling station" and such combinations and sub-combinations of the structure as the same may be used in the dispensing pump art, all as will be more particularly pointed out and clearly defined in the appended claims.

25 It is now the custom for dealers in gasoline and oils to place dispensing pumps at the curb or other outdoor positions convenient for the buyer of the oil. It is common practice among pump manufacturers to build a cover or protecting casing for outdoor use of such pumps as were previously used indoors without casings. So far as I am aware, the pumps heretofore used outdoors are substantially the same in construction and operation as the pumps previously used indoors except for the addition of the casing. This prior practice results in exposing the larger portion of the operating parts of the pump whenever the same is in use. The casing in such practice is designed to thoroughly protect the pump only when the pump is not in use which, as a rule, is only a small part of each day. This objection is caused by the fact that the pump is not designed for use with the casing, and the latter must necessarily take the form determined by the old style of pump which aggregated arrangement of pump and casing is a makeshift at best. To illustrate the prior arrangement, reference is made to Patent No. 1,108,673, of August 25, 1914.

30 The objections to the former practice increase as the size of the pumps increase. For example, what may be suitable and con-

venient enough for a one gallon pump will be wholly unsuitable and inconvenient as well as extremely unsightly when adopted for a five gallon pump.

5 The object of this invention is to provide a dispensing apparatus more particularly for outdoor use in which the pump is specially designed for combined use with and to be protected by an improved casing, such apparatus being characterized by the location of the operating parts of the pump side by side with the pump cylinder and closely adjacent thereto so that the cylinder and associated mechanism may be effectively protected and covered at all times.

10 The object of this invention is to combine a pump and casing, the combination being characterized by the location of the greater portion of the pump mechanism within the casing for permanent protection, the provision of means to most conveniently operate the pump while effectively inclosed and means on the pump extending outside of the casing and co-operating with parts on the casing to indicate at all times the piston displacement of the pump.

15 A third object of the invention is to provide an improved dispensing pump of the reciprocating piston type for outdoor use with a casing having its operating parts covered and protected at all times by the casing, except an exposed handle and exposed means to indicate at all times the position of the piston within the casing.

20 A fourth object of the invention is to provide an improved dispensing pump of the reciprocating piston type particularly designed for outdoor use with a suitable cover for the operating parts of the pump.

25 A fifth object of the invention is to provide an improved cover casing for an outdoor pump, said casing having parts thereon to co-operate with means on the pump whereby the operation of the pump may be carried on as desired when covered and protected.

30 A sixth object is to provide an improved pump for outdoor use which may be made in large sizes without unduly increasing the objections to outdoor pumps.

35 Other objects of the invention will be apparent from the following description and annexed claims.

40 With these objects in view, the invention

will be described by reference to one preferred and illustrative example.

Figure 1 is a side elevational view of the pump;

5 Fig. 2 is a front elevational view thereof;

Fig. 3 is a rear elevational view of the indicating scale shown in Fig. 2;

Fig. 4 is an enlarged cross sectional view taken on the line 4—4 of Fig. 3;

10 Fig. 4^a is an enlarged vertical section of the indicating scale;

Fig. 5 is a rear elevational view of the pump with the casing members broken away to reveal the mechanism therein;

15 Fig. 6 is an elevational view taken from the left of Fig. 5, the casing members being broken away;

Figs. 7, 8, and 9 are cross sectional views taken on the lines 7—7, 8—8, and 9—9, respectively, of Fig. 5;

20 Fig. 10 is a cross sectional view, taken on the line 10—10 of Fig. 6, of the pump cylinder and piston;

Fig. 11 is a detail sectional view showing 25 the connection of the operating handle to the driving mechanism; and

Fig. 12 is a sectional elevation taken on the line 12—12 of Fig. 1.

Referring to these drawings in detail and 30 particularly to Figs. 5 and 6, a base casting 15 supports a pump cylinder 16 and formed in the base casting is a pump inlet 17 to which liquid is supplied in the usual manner through a pipe 18. On the top of cylinder 16 is a cap member 19 which is held to the base casting with the cylinder 16 clamped therebetween by a plurality of bolts 20. The casting 15 has a circular flanged base 21 and cap 19 a circular top 22. Two 35 semi-cylindrical casings 23 fit together in abutting relation over the members 21 and 22 and completely inclose the space therebetween, whereby the pump cylinder as well as other mechanism to be described is concealed and protected against the weather and accidents generally.

The casing members 23 are hinged together on one side by two or more U-shaped links 24 (Figs. 5 and 9), each of which fits into 50 and connects a pair of sockets 25 secured to the interior of the casings 23 adjacent their plane of separation. The casings are connected in the described manner prior to assembly and are slipped around the parts 21 55 and 22 to encompass the latter. Substantially diametrically opposite from the sockets 25, other sockets 25' are secured to the interior of casings 23. The sockets 25' on one casing are arranged to come into vertical alinement with the sockets 25' on the other casing when the casings have been assembled and brought into the position shown in the drawings. A lug 23' (Figs. 2 and 6) on the base 21 is adapted to enter 60 a recess in one casing 23 to fix the circum-

ferential position of the casings relative to the members 21 and 22. A rod 24' passes vertically through member 22, through each pair of aligned sockets 25', and fits into a socket in the base 21, as shown in Fig. 5. A finger ring 22' is provided at the top of rod 24' to permit convenient removal of the latter when desired. The casings 23 are thus held in abutting relation to inclose the space between members 21 and 22 and are locked 75 to the latter by the rod 24'.

Secured to the upper face of member 22, as shown in Figs. 5, 6, and 9 is a cylindrical housing 26 which is closed at the top save for a centrally arranged elliptical opening. 80 Housing 26 has oppositely located cover plates 27 which rest in a flanged seat in the housing (Figs. 5 and 8) and may be removably secured thereto in any suitable manner. For example, lugs 28 (Figs. 5 and 8) 85 may be arranged to hook over the lower flange of the housing, and a lock (indicated conventionally by reference 29) is fastened to cover 27 and may be arranged to have its bolt engage in the upper flange as indicated, 90 so that the cover may be locked in place. Secured to the top of housing 26 (Figs. 1 and 2) is an upstanding hollow elliptical casing 30 and upon the top of the latter a cap standard 31 which may support an ornamental dome 32. Casing 30 is held to the standard 31 and housing 26 by the screws shown in Fig. 1.

Other means are provided to hold the casing 30 and standard 31 to the housing which 100 means are arranged to interiorly connect the parts in such a manner that they cannot be removed except by authorized persons. Referring to Fig. 12, two or more rods 31' are pivoted to the interior walls of standard 31' and depend vertically or substantially so within casing 30. The lower ends of rods 31' are adapted to fit into forked lugs 26' formed on the interior of housing 26 (see Fig. 7) and thumb nuts 30', threaded on the 105 lower ends of rods 31', clamp the casing 30 between the housing 26 and standard 31. It will thus be seen that the casing and standard cannot be removed until covers 27 have been unlocked and removed. The 110 thumb nuts 30' may be readily removed when covers 27 are removed and rods 31' may be then swung out of the forked lugs 26' to release the connected parts. The screws shown in Fig. 1 may be omitted if 115 desired.

The pump proper will be described briefly in general terms except for its operating means to which the invention is more particularly directed. Liquid is drawn in 125 through pipe 18 past the suction operated valve shown in Fig. 5 into cylinder 16 by the suction stroke of the pump. The liquid thus drawn into the pump can pass into either of two oppositely disposed outlets 130

which are formed in cap 19 and connected by suitable passages directly with the pump cylinder, one opening upwardly through plate 22 and the other downwardly into the interior of casings 23. To the former outlet an air dome 32 (Fig. 5) is secured which is disposed within housing 26 and functions in the usual manner. From the other outlet a pipe 33 extends downwardly and is connected by suitable fittings, as shown in Figs. 5 and 6, to the lower end of a filter 34, the latter and pipe 33 being arranged in U-form. From the top of filter 34 a discharge pipe 35 extends upwardly through plate 22 and housing 26 and terminates adjacent standard 31 with a suitable fitting. The usual "blow off" pipe for the filter is indicated at 34' and this pipe terminates above the upper face of plate 22 and is provided with a valve 35' (Figs. 5 and 8) through which the filter may discharge for cleaning in the usual manner.

The piston of the pump, however, is of novel and advantageous construction. It comprises a circular disk 37, secured as shown in Fig. 6 to a piston rod 38, and having a plurality of openings 39 extending therethrough. Upon the upper face of disk 37 is a circular disk 40 of suitable material, such as leather, for example, which is slightly larger in diameter than cylinder 16. Resting upon disk 40 is a small disk 41 (Fig. 10) which is formed with a plurality of radially arranged spring fingers 41'. Disks 40 and 41 are centered on the member 37 by the piston rod 38 and are held against the member 37 by a weight 42 which loosely fits the piston rod, as shown in Fig. 6. The lower face of weight 42 is chamfered, as shown in Fig. 6, to permit upward movement of fingers 41'. On the down-stroke of piston rod 38, the disk 40 and fingers 41' yield to permit liquid to pass through openings 39, but on the up-stroke disk 40 is held to member 37 by spring fingers 41' and the pressure of the liquid thereabove. The structure described is characterized in that an efficient piston is provided which is of simple construction and adapted for low cost of manufacture. For example, the member 37 may be simply a rough casting upon which no finishing operations are necessary save for the drilled hole for piston rod 38. The disks 40 and 41 may conveniently be formed by stamping and the weight 42 may consist simply of a rough casting.

The means for actuating the piston will now be described. Piston rod 38 extends upwardly through a suitable stuffing box in plate 22 and secured to the upper end of the rod in T-form is a cross head 45. Fixed to the extremities of the latter are two rods 46, hereinafter called the operating rods, which are arranged one on each side of the piston rod and extend down-

wardly through bearing bushings 50 in plate 22 to a position adjacent the lower end of the piston rod, as shown in Fig. 6. The operating rods are thus arranged in parallel and overlapping relation with the piston rod. A pair of rods 47, hereinafter called guide rods, are arranged in parallel relation with the operating rods and as shown in Fig. 9, are disposed in the same vertical plane as the operating rods and piston rod. These rods 47 fit into sockets in the base 21 and extend upwardly through and terminate flush with the top of plate 22, each rod being held in position by a pin 48 applied just below plate 22, as shown in Figs. 5 and 6. Fixed to the end of each operating rod is a guide block 49 which, as best shown in Fig. 9, encircles the adjacent guide rod and has a slideable engagement therewith. The operating rods thus have bearings in the plate 22 and on the guide rods. In order to provide bearings of adequate length in the relatively thin plate 22 for the rods 46, relatively long bushings 50 are provided which are held to the plate by nuts 51 co-operating with the flanges shown on the bushings in Figs. 5 and 6.

Rotatably mounted in the base casting 15 and below the inlet passage 17 is a horizontal shaft 52 which extends entirely through the pedestal and has fixed on each end a sprocket 53. Vertically above each of the latter is an idler sprocket 54 rotatable on a stud 55 fixed in the cap 19. A sprocket chain 56, adjustable for length by a turn-buckle 57 connects one pair of sprockets 53 and 54, and a similar chain connects the other sprockets 53 and 54, and the inner travel of each chain is in parallel relation with and closely adjacent to an operating rod 46. Each guide block 49 has two spaced projections 58 which, as shown in Fig. 5, pass through the openings between adjacent links of chain 56 and are held to the latter by pins 59. It will thus be seen that, as sprockets 53 are turned in a clockwise direction (as viewed in Fig. 5) the chains 56 will lift operating rods 46 and the latter, acting with equal force on opposite sides of the crosshead 45, will lift the piston rod 38 vertically. The return or downstroke of piston rod 38 is effected by the weight of the parts connected thereto and the weight of described member 42 associated therewith.

The means for operating the shaft 52 will now be described with particular reference to Figs. 5 and 6. A relatively large sprocket 61 is fixed to shaft 52 near one end thereof and is connected by a chain 62 to a relatively small sprocket 63 which is mounted to one side of sprocket 54 but in the same horizontal plane therewith. The sprocket 63 has at diametrically opposite points two projections 64 which extend axially outward from the face of the sprocket and are adapted to

fit in mating recesses in an operating handle 65, as shown in Fig. 6. Handle 65 has been purposely omitted from Fig. 5.

The detail of the mounting of handle 65 and sprocket 63 is clearly shown in Fig. 11. The sprocket 63 is rotatable on a stud 66 and is held from axial movement thereon by a set screw 67 which loosely rides in a circumferential groove 68 in the stud. The latter has integrally formed thereon in eccentric relation a cylindrical part 69 which is fixed in cap 19 by a set screw 70. By loosening the latter and turning stud 66, the axis of the sprocket 63 may be raised or lowered to alter the tension in chain 62, as desired. Handle 65, as shown in Fig. 6, has a part which passes loosely through an opening in casing 23 to engage the projections 64 and loosely mounted in this part is a rod 71 which is adapted, as shown in Fig. 11, to screw into the end of stud 66. Upon rod 71 are two spaced circumferential flanges 72 which loosely fit the bore of handle 65 and a screw 73 is threaded into the latter and extends between the flanges and in the path thereof. A spring 74 coiled around rod 71 acts between one flange 72 and a shoulder on the interior of the handle to hold the latter in engagement with projections 64. Thus by turning handle 65, the sprocket 63 may be turned to lift the pump piston, but, instead of turning the handle in a reverse direction to lower the piston, the preferred operation is to pull the handle axially outward to disconnect it from projections 64 whereby the down-stroke will be effected by the weight of the parts, as described. In this return or lowering operation of the pump piston, the handle does not, therefore, need to rotate. The engagement of screw 73 with the outermost left hand flange 72, as shown in Fig. 11, limits the outward movement of the handle. The removal of the latter may be made when desired by turning the rod 71 by the exposed portion thereof.

In order that the operator may cause the delivery of predetermined quantities from the pump, measuring stops are provided to limit the movement of the piston rod. These measuring stops will now be described with particular reference to Figs. 6, 8, and 9. A rod 75 is mounted vertically in spaced parallel and adjacent relation with one of the operating rods 46 and, as shown in Fig. 9, is arranged at right angles to the guide block 49 and on the opposite side of rod 46 from the chain 56. Rod 75 is supported at its lower end in the base casting 15, and its upper end passes through plate 22, a collar 76 being provided on the rod to engage the lower face of the plate. Fixed to the upper face of the latter (Fig. 8) is an arcuate dial plate 77 having graduations thereon.

In the embodiment illustrated these grad-

uations indicate one, three, and five gallon quantities. A pointer 78 is fixed to the upper end of rod 75 and may be turned by the handle shown whereby the rod may be moved to various angular positions to effect the delivery of measured quantities as will appear. Fixed in suitably spaced relation on rod 75 and at right angles to one another (Fig. 9) are blocks 79 in each of which a bolt 80 is threaded from below. A suitable lock nut is provided in each bolt as shown in Fig. 6 to engage the upper face of its block 79. The heads of bolts 80 are adapted, when suitably turned, as described, to lie in the path of a lug 81 (Fig. 9) on one of the guide blocks 49, and thereby limit the upward travel of the operating rods. The lower bolt 80 is adapted to arrest the operating rods when one gallon has been delivered from the pump and the upper bolt when three gallons have been delivered. Above the upper block 79 and adjustably fixed to rod 75 is a circular disk 83 which is adapted to engage lug 81 whatever the angular position of rod 75, provided only that neither bolt 80 is disposed in the path of the lug. Disk 83 arrests the operating rods when the full capacity of the pump, say, for example, five gallons, has been delivered. Thus, the operator, by the use of pointer 78 and dial 77 may conveniently set the stops described to effect the delivery of measured quantities from the pump.

The measuring stops described are not, however, visible to the customer and are intended primarily for convenience in operating the pump, as other means, visible from the exterior of the pump, are provided to indicate to the customer the quantities dispensed. The visible indicating means will now be described with reference to Figs. 2 to 7, inclusive. The piston rod 38, operating rods 46, and cross head 45 are, as shown in Fig. 7, freely movable vertically within the elliptical casing 30. Fixed to one of the operating rods is a rod 85 which is bent, as shown in Fig. 6, to extend outwardly through a vertical slot 86 in casing 30. On the end of rod 85 is a forked pointer 87 (Fig. 7) which loosely fits over a plate 88, suitably secured to the casing. The outer face of plate 88 is visible to the customer and the rear face to the operator since the latter, when manipulating handle 65, faces the left hand side of the pump, as viewed in Fig. 7, and thus is in a position to observe the rear face of plate 88. The latter is not directly graduated, but the graduations are applied to both sides of the plate by means of buttons which are adjustable in the plate, as will now be described. Referring more particularly to Figs. 3 and 4, plate 88 has a series of vertically spaced circular openings 89, the centers of which are spaced one from another a distance equal

approximately to the desired distance between the graduations. For example, six openings are provided in the embodiment illustrated, the centers of which indicate approximately the vertical position necessary for the pointer 87 to assume to cause the delivery of one, two, three, four, and five gallon quantities. The desired marks and graduations are applied to circular disks 90, as shown in Figs. 2 and 3. For each opening 89, two disks are used, one on each side of the plate 87, as shown in Fig. 4. One button of each pair, that on the rear face of plate 87, has a nut 91 soldered thereto which passes into the opening 89. A screw 92 passing loosely through the other button of the pair is threaded into nut 91 so that the disks may be drawn together and clamped to the plate. It is to be noted that nut 91 is relatively small in comparison with opening 89 and that it may, therefore, be moved above or below the center of the opening so that there is a latitude of adjustment for the buttons. Thus, when the pump is tested, the buttons may be shifted up or down so that they exactly aline with pointer 87 when the respective quantities indicated by the marks on the buttons have been delivered from the pump. It is also to be noted that the inner faces of buttons 90 are concave, and the buttons are preferably made of spring metal. This is important since it permits screw 92 to be turned through a considerable angle even after buttons 90 are tightly clamped to the plate. The practical utility of this construction is to permit one of the two transverse openings 93 in each screw 92 to be moved into vertical alinement so that a wire or small rod 94 may be passed through vertically all the screws, as shown in Fig. 3. The upper and lower ends of wire 94 may then be passed rearwardly through openings in the top and bottom of plate 88 and be bent over and sealed as clearly shown in Fig. 2. Thus, all the adjustable disks on plate 88 may be conveniently sealed in their adjusted positions by a single means.

A further indicating device is provided which consists of a total register 95 (Figs. 5, 6, and 9). This register is of a type too well known in the art to need detailed description, and it will suffice to say that it is of the cyclometer type and indicates cumulatively the quantities dispensed from the pump. Register 95 is suitably secured to the described plate 22 and may be driven by a chain 96 from a sprocket on stud 55 which sprocket is located directly behind the sprocket 54, shown in Fig. 5.

The operation of the dispensing apparatus will now be described. Usually, when operating the pump at least one of doors 27 is removed so that the measuring stops 80 may be adjusted. The doors need not, however, be opened when the full capacity of the

pump is being delivered or when the stops 80 are not used. The latter are only for the convenience of the operator if he desires them in delivering less than the capacity of one stroke of the pump. The indicators 90 70 are the sealed means designed to insure the proper measure to a customer using ordinary precautions in buying liquid from the dispenser. The operator connects handle 65, as already described, to sprocket 63 and 75 turns the latter to elevate the piston in the described manner. On continued movement, one of the stops 80 on the disk 83 comes into play to arrest the upstroke of the piston, or the operator may gage the stroke of the 80 pump simply by watching the pointer 87. As soon as the upstroke of the pump has been effected, the operator preferably pulls handle 65 axially outward to disconnect it from projections 64, thereby allowing the 85 piston to descend rapidly by gravity. As soon as handle 65 is released, it is immediately forced back into engagement with sprocket 63 by the spring 74 and, as the handle is turned, the recesses therein will 90 soon engage projections 64. The described operations are repeated until the desired quantities have been dispensed. Handle 65 may then be readily removed and doors 27 95 replaced to render all the mechanism inaccessible.

It is to be noted particularly that all the mechanism, save that actually desired to be otherwise located, is housed below plate 22 within casings 23. The apparatus to which 100 frequent access is necessary is located within housing 26 and is conveniently accessible through the openings in the latter when plates 27 are removed. The driving mechanism and other devices within casings 23 are 105 readily and completely accessible by removing the casings which may be conveniently accomplished. The arrangement of the driving mechanism is important on account of the improved appearance of the apparatus obtained thereby and also because of the fact that the point of application of the crank handle is located adjacent the top of the pump cylinder rather than at a considerable distance thereabove. The arrangement 110 described is, therefore, of considerable practical utility especially with pumps of large capacity.

What I claim is—

1. In a dispensing apparatus, the combination with a pump cylinder, its piston and piston rod, of an operating member for said rod and depending therefrom, mechanism to lift said member and arranged alongside the cylinder, a casing to inclose the 120 pump and its operating mechanism, said casing having an extension to inclose the piston rod and said member in its reciprocatory movement, an actuating crank for said mechanism and located below the top 125 130

- of the pump cylinder, a slot in said extension, and a part movable with the piston and visible from the exterior of the casing whereby the pump may be operated and a measure 5 of the pump's operation observed without opening the casing.
2. A dispensing apparatus, comprising, a pump cylinder, a piston, a piston rod, a cross head on the top of the latter, depending 10 guide rods and stationary guiding means therefor, a chain connected to the lower end of one of the guide rods and means to move the chain to operate the piston.
3. A dispensing apparatus, comprising, a 15 pump cylinder, a piston, a piston rod, a cross head on the top of the latter, depending guide rods and stationary guiding means therefor, a chain connected to the lower end of one of the guide rods and means to move the chain to operate the piston, said piston having sufficient weight associated therewith to lower the piston, the rod, and the cross 20 head from their upper to their lower positions.
- 25 4. A dispensing apparatus, comprising, a piston pump, a cross head connected to the piston rod with depending guide members, means to lift the cross head and located below the latter, a casing to inclose and protect said parts during a complete cycle of 30 their operations, a relatively small opening in said casing, and means extending from the cross head through said opening
- to move with the cross head relatively to the casing, to indicate outside of the latter the 35 piston displacement.
5. A dispensing apparatus, comprising, a pump cylinder, a piston and piston rod therefor, an upper header member and a lower header member, shafts and sprockets 40 on both header members, chains connecting suitable sprockets to form a power transmitting device, and means connecting said device with the piston rod, whereby the latter may be raised. 45
6. A dispensing apparatus, comprising, a pump cylinder having upper and lower header members, actuating means located in part on the upper and in part on the lower header members, and a piston rod having a 50 depending operating member connected at its lower end with said power means.
7. In a dispensing apparatus, the combination with a vertically-arranged pump with sufficient weight associated with its 55 piston to automatically move the latter from upper to lower position, a piston rod having a depending operating member, a mechanism located entirely below the top of the pump cylinder to lift said member, and an actuating member for said mechanism movable to temporarily release the mechanism, whereby the piston and its associated weight 60 may travel quickly to its lower position.

JOHN B. DAVIS.
